UNITED STATES PATENT OFFICE.

FREDRICH J. WALKER AND FRANK C. LOEFFLER, OF DES MOINES, IOWA.

SPARK-PLUG.

1,080,089.

Specification of Letters Patent.

Patented Dec. 2, 1913.

Application filed January 9, 1912. Serial No. 670,301.

To all whom it may concern:

Be it known that we, FREDRICH J. WALKER and FRANK C. LOEFFLER, citizens of the United States, residing at Des Moines, in the county of Polk and State of Iowa, have invented a new and useful Spark-Plug, of which the following is a specification.

The object of our invention is to provide a spark plug of simple, durable, and inexpensive construction, adapted to be used with an ordinary internal combustion engine, so constructed and arranged that the spark gap may be increased or decreased as desired by means controlled from the outside of the cylinder.

More particularly, it is our object to provide a spark plug in which one of the wires between which the spark gap is formed, may be easily moved longitudinally of the spark plug, by means operated from outside the cylinder and may be held in any position of its movement.

A further object is to provide a spark plug of such construction as to permit only a minimum of oil or other matter to drop into the combustion space in the upper end of the plug and at the same time to give a maximum of such combustion space.

Our invention consists in certain details, in the construction arrangement and combination of the various parts, whereby the objects contemplated are attained, as hereafter more fully set forth, pointed out in our claims, and illustrated in the accompanying drawings, in which—

Figure 1 is a side elevation of a spark plug embodying our invention. Fig. 2 shows a vertical, central, sectional view of the same. Fig. 3 is a top or plan view of the inner end of our spark plug, and Fig. 4 is an inverted plan view of the outer end of said spark plug.

In the accompanying drawings, we have used the reference numeral 10, to indicate the angular body of the spark plug, on which is formed a screw threaded extension 11, designed to be received in a screw threaded opening in a cylinder. In the screw threaded extension 11, is a recess 12, and in the body 10 is a screw threaded recess in which is received a screw plug 13. The recess 12 communicates with the recess in the body 13, by means of an opening 14. The opening 14 is of smaller diameter than the opening 12, and the opening in the body

10. The screw 13 is provided with a longitudinal opening.

Mounted in the longitudinal opening in the screw 13, is an elongated porcelain body 15, which is provided with an annular ring 16, designed to rest adjacent to the end of the screw 13 in the opening in the body 10, as shown in Fig. 2. The porcelain 15 extends from a position approximately flush with the end of the extension 11 to a point 60 beyond the outer end of the spark plug. On the outer end of the porcelain is a metal cap 17. Extending longitudinally through the porcelain 15, and through the cap 17, is a wire 18, for conducting electricity. The 70 outer end of said wire 18 is screw threaded, and on said screw threaded end, is mounted a metal cap 19. On the inner end of the wire 18, is a head 20, the inner end of which is approximately flat, as shown in Figs. 1, 75 2, and 3, which, as shown in Fig. 2, has the shape of a truncated cone, the sides of which are incurved. Near the outer edge of the outer surface of the body 10, is a screw 80 threaded opening, in which is mounted a screw 21, said screw threaded opening being inclined from the outer side of the body 10, toward the inner end of the spark plug, and toward the center thereof. Communicating with the opening 12, and the inclined opening last described, is a small opening inclined in the same direction as said first inclined opening. In the screw 21 is a longitudinal opening, which registers with the inclined opening last described. Mounted 85 in the screw 12 and in the second inclined opening in the body 10, is a wire 22 for conducting electricity. The outer end of the wire 22 is screw threaded, as is the opening in the screw 21, and on the outer end of the 90 wire 22 is a head 23. It will be noted that the inner end of the wire 22 is not sharp, but rounded as shown in Fig. 2. It will thus be seen that the wire 22 is inclined from a point near the outer edge of the outer end 95 of the body 10, toward the center of said body, and toward the inner end thereof. The inner end of the wire 22 is designed to be near the head 20. On account of its screw threaded outer end, it can be screwed 100 closer to or farther from the head 20, thus diminishing or increasing the spark gap between the head 20 and the wire 22. Around the wire 22 at the inner end of the screw 21, we place suitable packing material 24. 105 110

In the practical use of our improved spark plug, the extension 11 is screwed into a screw threaded opening in the cylinder, and the current conducting wires are connected with 5 the wires 18 and 22. It will be readily seen that the spark gap between the inner end of the wire 22, and the head 20, may be increased or diminished.

The advantages of a device of this kind 10 are obvious. It frequently occurs that in two cylinders in the same engine, the spark gap should be of different width, and in the spark plugs in ordinary use, the width of the gap can be varied only by removing the 15 spark plug from the cylinder and bending the inner ends of the electricity conducting wires. In our device, by longitudinally adjusting the wire 22, the distance of the spark gap may be varied as desired. The pitch 20 of the screw threads of the wire 22 and the screw 21 may be such that the spark plug may be very accurately adjusted. Our device is of simple, durable, and inexpensive construction, and can be used with any ordinary 25 gasoline engine. The form of the head 20 is such that it allows only a minimum of oil to drop into the combustion space or chamber. The size of the opening 12 is 30 large enough to form a considerable combustion space. The inclination of the wire 22 is such as to enable us to locate a screw 35 23 at a convenient point for operation outside the cylinder and spaced from the porcelain 15.

35 We claim as our invention:

1. In a device of the class described, a spark plug body, an elongated insulating body detachably mounted therein, an electrode detachably mounted in said insulating 40 body, its inner end extending beyond said body, clamping means on the outer end thereof for securing a current carrying wire thereto, said body being provided with a passage for a second electrode extending 45 obliquely through said body from a point within the cylinder when the body is attached thereto to a point outside said cylinder and with an enlarged internally screw threaded recess at the outer end of said 50 opening, a ground electrode adjustably mounted in said opening and extending from a point near the inner end of the first electrode at an acute angle thereto to a point outside the outer end of the spark plug body, 55 said ground electrode being screwthreaded over the outer portion of its length; a head

on said ground electrode, a screwthreaded plug mounted in said recess, said screwthreaded plug being provided with a screwthreaded opening in which the screwthreaded portion of said ground electrode is received, and with a head on its outer end, and packing material in said recess between said screw threaded plug and said body. 60

2. In a device of the class described, a spark plug body having recesses at both ends and a partition between said recesses in which is an opening, an elongated insulating body having one end extended through said opening and provided with a shoulder 70 adjacent thereto, a plug mounted on said insulating body and screwed into one of the said recesses in said spark plug against said shoulder, an electrode extending longitudinally through said insulating body, a ground 75 electrode slidingly mounted in said spark plug body, and extending from a point near the inner end of the first electrode at an acute angle thereto, through the spark plug body, to a point outside the same, a plug 80 screwed on said ground electrode and screwed into said body, and a head on the outer end of said ground electrode.

3. In a device of the class described, a spark plug body, having a recess at its inner end an insulating body mounted therein, an electrode mounted in said insulating body its inner end extending beyond said body, clamping means on the outer end thereof for securing a current carrying wire thereto, a ground, a second electrode adjustably mounted in said insulating body and extending from a point near the inner end of the first electrode at an acute angle thereto and extending to a point outside the outer end 90 of the spark plug body, said ground electrode being screwthreaded over the outer portion of its length, a head on said ground electrode a screwthreaded plug mounted in the outer end of said spark plug body, said 100 screwthreaded plug being provided with a screwthreaded opening in which the screwthreaded portion of said ground electrode is received, and a head on said screwthreaded plug.

Des Moines, Iowa, December 30, 1911.
